Primary Examiner — Mary Ann Calabrese(74) *Attorney, Agent, or Firm* — Stinson Leonard Street LLP(57) **CLAIM**

The ornamental designs for a lighting assembly, as shown and described.

DESCRIPTION

FIG. 1 is a perspective of a lighting assembly.

FIG. 2 is a front elevation thereof.

FIG. 3 is a rear elevation thereof with a housing assembly omitted for clarity of illustration.

FIG. 4 is another rear elevation thereof with the housing assembly shown.

FIG. 5 is a right side elevation thereof.

FIG. 6 is a left side elevation thereof.

FIG. 7 is a top plan view thereof; and,

FIG. 8 is a bottom plan view thereof.

The stippled shading illustrates a contrasting surface appearance.

The broken lines in the drawings indicate environmental structure which forms no part of the claimed design.
